UNITED STATES PATENT OFFICE

OSCAR ONSRUD, OF CHICAGO, ILLINOIS, ASSIGNOR TO ONSRUD MACHINE WORKS, INC.,
OF CHICAGO, ILLINOIS, A CORPORATION OF ILLINOIS

CLAMP MOUNTING FOR AUTOMATIC SHAPERS

Application filed August 24, 1931. Serial No. 559,087.

This invention relates to improvements in the mounting of pneumatic clamps for use in holding work upon a machine while cutting operations are performed upon the work. The construction is useful in such machines as described in applicant's co-pending application for patent, Serial No. 506,134, filed January 2, 1931, on automatic shaper; or the constructions described in applicant's Patents Nos. 1,715,380, of June 4, 1929; 1,685,613, of September 25, 1928; and 1,685,572, of September 25, 1928.

The machines described in the above mentioned application for patent, and patents, include a circular rotating table upon which is supported a plurality of articles to be operated upon as the table rotates such articles past cutting tools which are relatively stationary. The clamps are carried along with the table, and are successively actuated to engage and release the articles supported upon the table. Actuation of the clamps is generally accomplished by a rotating valve structure centrally located with reference to the table, and connected by flexible conduits with the separate clamps.

It is necessary, according to the character of the work operated upon, to provide for different radial and vertical positions of the clamps with reference to the work table. Frequently the table carries forms or patterns as well as the work operated upon, and provision is made for either supporting the clamps directly upon the table or upon such forms.

In order to avoid the necessity of mounting the clamps directly upon the rotating work table or articles supported thereon, this improved construction provides for correctly positioning the clamps, both radially and vertically, with reference to the work table, more rapidly than is possible with prior arrangements.

The objects of the invention are to provide improvements in clamp mounting for ma-

chines of the class mentioned, for rapidly effecting radial and vertical positioning of the clamps, and to nevertheless rigidly support the clamps and resist upward thrust thereof against the downward clamping motion of the clamping elements thereof.

The objects of the invention are accomplished by means of a construction illustrated in the drawing, wherein:

Figure 1 illustrates in side elevation the improved clamp mounting means, and a clamp carried thereby. Duplicated parts are omitted from this view.

Figure 2 is an end view of the construction shown in Figure 1, and is partly in section, as indicated by the line 2—2 of Figure 1.

The clamp mounting means to which this invention relates is a heavily constructed unit provided with a supporting casting arranged to be bolted centrally upon the rotating work supporting table. This casting supports a plurality of vertical posts equally spaced from the center thereof and connected at their upper ends by a spider having a central ring for convenience in lifting and placing the clamp mounting unit on the work table.

Each post carries a collar at each end, one of which is rigid and the other slidably mounted upon the post. Carried by these collars is a horizontal extensible linkage arranged to resist upward thrust and carrying at its outer end a tube corresponding to the fixed post, and likewise having one fixed collar and one sliding collar thereon, to which the linkage is pivotally connected.

Vertically adjustable within each tube is a shaft which carries at its lower end one of the pneumatic clamps. Each clamp is adjustable angularly around its supporting shaft and the latter is prevented from turning within the sleeve.

The extensible linkage is a lazy tong construction having clamping bolts at some of its pivots so that it may be rigidly secured against motion in any of its extended posi-

tions. This arrangement when carefully made and closely fitted, affords a rigid bridge-like structure well adapted to resist upward thrust at its outer end.

The construction as illustrated in the drawing consists of a central supporting casting 1 having bolt holes 2 for attachment to a work supporting table and being hollowed out, as indicated at 3, to provide space for a rotating valve construction carried by the work supporting table within the ring-like base of casting 1. The upper end or head 4 of casting 1 is provided with vertical apertures 5 for receiving posts 6. The posts may be rigidly secured in place by bolts 7. These bolts pass through ears 8, adjacent the saw cuts 9 extending from the apertures 5 to the periphery of the casting.

The upper ends of the posts 6 are connected together by a spider 10 fastened to the posts by screws 11 and having a center lifting ring 12. Each post 6 carries a collar 13, which is rigidly secured to the post near the lower end thereof by means of pins 14. A similar collar 15 may slide along the post. The lower collar has an outwardly extending ear 16, on each side of which is a link 17 pivoted to the ear by means of a clamping bolt 18. Between the links 17, and centrally pivoted thereto at 19, is a link 20, which is pivoted by clamping bolt 21 between a pair of ears 22 on the collar 15. The links 17 and 20 at their opposite ends may be pivotally connected directly or through similar linkage as indicated at 23, 24 in Fig. 1, to a sliding collar 25 and a fixed collar 26 on a hollow post 27. The post 27 is secured to collar 26 by pin 28. The links 23 and 24 are respectively connected with ears on the collars 26 and 25 by the clamping bolts 29 and 30.

A pneumatic work engaging clamp 31 is secured to the bottom end of a shaft 32 fitted within the sleeve 27. This shaft is adjustable within the sleeve by means of a screw 33 carried at the upper end of collar 25, and having threaded engagement at 34 with the shaft. The shaft is slotted at 35 and pin 28 passes through this slot, thus preventing the shaft from turning within the sleeve. The pneumatic clamp is angularly adjustable around the shaft and is clamped in any desired position by the bolt 36. The clamp 31 comprises a piston chamber 37, within which is mounted a pneumatically operated piston for actuating the pivoted jaw element 38 of the clamp. Air under pressure is admitted and released from the piston chamber through a tube 39, which leads to a control valve, not shown, but mounted on the hollow base 1.

For convenience in locating the clamps with reference to the work operated upon, each clamp carries a vertically slideable pin 40, which may drop into a hole provided in a pattern carried by the work supporting table.

The operation of the clamp supporting structure as described is a mere matter of adjustment. To position clamp 31 radially with reference to the supporting member 1, the bolts 18, 21, 29 and 30 are loosened, and post 27 is moved toward or away from post 19, the linkage between these posts being folded or extended while the collars 15 and 25 slide along the posts, according to the movements of the links toward or away from the horizontal position. The adjustment of clamps 31 vertically is effected by screws 33, which when turned, move the supporting shafts 32 for the clamps, in an axial direction, while the same are prevented from being turned by pin 28. Angular adjustment of the clamps around the axis of the supporting shafts therefor, is possible when the screw 36 is loosened.

Although but one specific embodiment of this invention is herein shown and described, it will be understood that certain details of the construction shown may be altered or omitted without departing from the spirit of this invention as defined by the following claim.

I claim:

A clamp supporting structure of the class specified, comprising a rigidly mounted vertical post having one collar fixed thereto and another collar slidably thereon, links pivotally connected together intermediate their ends, each having one end pivoted to one of said collars, means connecting the opposite end of one of said links with the vertically extending clamp supporting post, a clamp on said post, a collar slidably on said post and operatively connected with the end of the other of said links, said second mentioned post being hollow, a shaft fitting within said hollow post, a clamp secured to said shaft, and means for adjusting said shaft longitudinally within said post.

Signed at Chicago, in the county of Cook and State of Illinois, this 19th day of August, 1931.

OSCAR ONSRUD.
